UNITED STATES PATENT OFFICE.

HORACE ST. JOHN DE AULÀ DONISTHORPE, OF LONDON, ENGLAND.

RADIO TELEGRAPHIC AND TELEPHONIC APPARATUS.

1,388,936.

Specification of Letters Patent. Patented Aug. 30, 1921.

Application filed April 28, 1920. Serial No. 377,274.

To all whom it may concern:

Be it known that I, HORACE ST. JOHN DE AULÀ DONISTHORPE, subject of the King of Great Britain and Ireland, residing at 5 Chancery Lane, London, in the county of London, England, have invented new and useful Improvements in Radio Telegraphic and Telephonic Apparatus, of which the following is a specification.

10 This invention relates to improvements in wireless telephonic and telegraphic apparatus and more particularly to portable receiving sets or apparatus.

This invention consists of a portable wireless telephonic and telegraphic receiving set comprising inductances, a detector, telephonic terminals and electrical connections made up in book form so that the wave length is varied by opening or closing the book. A further feature of this invention resides in the combination with the book receiving set of a telephone plug and telephones. This invention is also characterized by the fact that means are provided for maintaining any predetermined wave length or angular relationship of the hinged parts. Further features will transpire in the following description of the accompanying drawings, in which:—

30 Figure 1 is a plan or open book view showing certain parts and a diagram of the electrical connections.

Fig. 2 is a section through the closed book showing details of construction.

35 Fig. 3 illustrates the method of varying the wave length by changing the angular relationship of the hinged book parts.

Referring to Figs. 1 and 2 the apparatus comprises hinged book parts 1 and 2 connected to a tubular hinge member 3 and connected by hinges 4. The hinges have been omitted from Fig. 1 for the sake of clearness. Built into each book part or cover are inductances 5 and 6 preferably 40 formed of edge-wound flat metal strip and connected by an electrical conductor 7. Spring screw or other type terminals 8 and 9 in the cover 1 serve respectively for connecting up the aerial 10 and earth connection 11. Conductors 12 and 13 connect the terminals to the respective inductances 5 and 6. Metal corner plates 14 and 15 are fitted as shown.

The tubular hinge member 3 contains a 55 vulcanite or other insulating tube 16 into

which is fitted at one end a detector element 17. A rod 18 passing through a metal bush 19 in the vulcanite tube carries at its extremities a coöperating detector unit 20 and a head or knob 21. A spring 22 interposed between bush 19 and detector unit 20 maintains the latter in contact with unit 17 and the knob serves for turning unit 20 to present new points of contact between the detector crystals. An electrical conductor 23 connects bush 19 with the aerial terminal 8.

At the other end of the tube 16 a plug socket 24 and a metal bush 25 are fitted. Conductor 26 connects the socket to detector unit 17 and conductor 27 connects bush 25 to the earth terminal 9. The detachable metal telephone plug 28 is bored to take an insulating sleeve 29 through which passes an electrically conductive rod 30 carrying a plug 31 engaging in socket 24. Plug 28 is shaped to fit bush 25 and a binding screw 32 secures the telephone lead 33. Telephone lead 34 is secured to the insulated rod 30 by a binding screw 35. One or a pair of telephones of suitable type are indicated at 36. 80

Any suitable type of hinge may be fitted and in cases where hinges are used of the type in which the parts do not retain their angular relationship by friction then means are provided for locking the hinge parts or 85 the book parts in any predetermined angular position.

The operation of the receiving set described above is as follows: To receive signals the telephones are plugged into the book 90 the aerial connected to terminal 8 and an earth connection to terminal 9. With the book closed as at 43 in Fig. 3 the set will be tuned to a predetermined wave length. As the angular relationship of the two book 95 parts or covers is varied as for instance in the positions 44, 45, 46 and 47 the wave length is varied. The variometer effect thus obtained varies in range as desired and according to design.

100 Although one preferred form of construction has been described above, various modifications may be made as required. For instance a so-called cartridge type detector may be adapted to be inserted into the hinge tube to make contact with and be retained by suitably connected clips. The aerial and earth connections may take the form of plugs and where a telephone blocking condenser is required a suitable condenser 48 110

may be built in between the thicknesses or boards of the covers or book parts and suitably connected up.

Although a pocket book wireless receiving set has been described above, the invention is not necessarily in this respect limited but may be carried out without limitation as to practical dimensions.

I claim:

10 1. A wireless telephonic and telegraphic receiving set comprising in combination two book parts and a hollow hinge part with inductances, a detector, a condenser, telephone terminals, aerial and earth terminals and 15 electrical connections contained therein, telephones and means for connecting the telephones in operative relationship to the receiving circuit.

20 2. A wireless telephonic and telegraphic receiving set comprising two book parts and a hinge part, hinges connecting the book parts, inductance coils in each book part, a condenser, an aerial terminal and an earth terminal each in one book part, electrical 25 conductors connecting said terminals and inductance coils to establish a receiving circuit, a detector, telephone contacts, an electrical conductor connecting one detector element to the aerial circuit, an electrical conductor connecting the other detector element to one telephone contact, telephone receivers, a plug connecting the telephones in the detector circuit and an electrical conductor connecting the other telephone contact to 30 the earth terminal.

35 3. A wireless telephonic and telegraphic receiving set comprising two book parts and

a hinge part, hinges connecting the book parts, inductance coils in each book part, an aerial terminal and an earth terminal in one 40 book part, electrical conductors connecting said terminals and inductance coils to establish a receiving circuit, a detector in the hinge part, telephone contacts in the hinge part, an electrical conductor connecting one 45 detector element to the aerial circuit, an electrical conductor connecting the other detector element to one telephone contact, telephone receivers, a plug connecting the telephones in the detector circuit and an electrical conductor connecting the other telephone contact to the earth terminal.

4. A wireless telephonic and telegraphic receiving set comprising two book parts and a hinge part, an inductance coil in one book 55 part, an inductance coil in the other book part, a connection for the aerial and a connection for the earth wire in one book part, flexible electrical connections between said inductance coils aerial and earth connections 60 establishing a receiving circuit, a detector in said hinge part, a flexible electrical conductor connecting one detector element to the aerial circuit, a flexible electrical conductor connecting the other detector element 65 to one telephone contact located in said hinge part, a telephone receiver, a second telephone contact in said hinge part connected to the earth terminal, a concentric plug connecting the telephone in the detector circuit and 70 hinges connecting said book parts said hinges being adapted to retain said book parts in any predetermined angular relationship.

HORACE ST. JOHN de AULÀ DONISTHORPE.
